[57] CLAIM

The ornamental design for a pull cord grip, as shown and described.

DESCRIPTION

FIG. 1 is a perspective view from one end and side of a pull cord grip showing my new design;

FIG. 2 is a side elevation view thereof, the other side elevational view the same;

FIG. 3 is an end elevational view thereof, the other end elevational view being the same; and,

FIG. 4 is a cross-sectional view thereof, taken along the line 4—4 of FIG. 3.

Fig. 1.

Fig. 2.

Fig. 3.

Fig. 4.
